UNITED STATES PATENT OFFICE.

NAHUM HAYWARD, OF ROANOKE, INDIANA.

IMPROVEMENT IN BRIDLE-BITS.

Specification forming part of Letters Patent No. 122,383, dated January 2, 1872; antedated December 23, 1871.

To all whom it may concern:

Be it known that I, NAHUM HAYWARD, of Roanoke, in the county of Huntington and State of Indiana, have invented a certain Improvement in Bridle-Bits; and I do hereby declare that the following is a full, clear, and exact description thereof, reference being had to the annexed drawing making a part of this specification, in which—

Figure 1 is an elevation of my improved sliding bit, showing the cheek-pieces, the sliding bars, the levers, and their connecting-link, and the rings in their outer ends. Fig. 2 is a side view, showing the parts above alluded to in a different position. Fig. 3 is an end view, showing the slots in the cheek-pieces for attaching the reins and the head-stall. Fig. 4 is an elevation of one of the levers having the ring formed in its end.

Corresponding letters refer to corresponding parts in the several figures.

This invention relates to bits to be attached to bridles and head-stalls to be used upon horses; and it consists in the construction, combination, and arrangement of such bits, as will be more fully explained hereinafter.

Various attempts have heretofore been made to construct a bit for horses' mouths that should be applicable for use upon horses that were docile and easily managed, and upon those vicious and at times nearly unmanageable; but such efforts have, as far as I am aware, been unsuccessful. My invention is designed to supply this want by furnishing a bit which may be used for or upon both of the classes of animals above described.

In constructing bits of this character I provide two cheek-pieces, A², of the form shown, or of any other suitable form that will admit of there being formed in it slots for the reception of the reins and for straps of the head-stall. To these cheek-pieces sliding bars A A¹ are firmly attached at one of their ends, they being semicircular upon their outer surfaces and flat upon their inner ones. These sliding bars are at such a distance apart as to permit the levers B B to play freely between them, so that as the cheek-pieces approach each other the bars may move freely upon the sur-

faces of the levers. The levers B B above alluded to may be of the form shown in Fig. 1, and be provided with rings in their outer ends for the reception of the reins or of the check-rein; or they may be of the form shown in Fig. 4, and have the ring formed in their ends. They are to be placed between the sliding bars A A¹, as shown in Fig. 2, and connected together by a link, B', as shown in Fig. 1. To the rings in the outer ends of the levers the reins are to be attached when the bit is to be used upon a vicious or hard-mouthed animal, in order that as such reins are pulled upon the levers B B shall be made to assume the positions shown in Fig. 1, which operation will press the cheek-pieces inward and against the cheeks of the animal, and carry the inner ends of the levers up against the roof of the animal's mouth and effectually control him.

When the bit is to be used upon docile animals the reins are to be attached to the slots in the cheek-pieces and the check-rein to the rings in the levers, which arrangement will permit the parts to remain in the positions indicated in Fig. 2; or the cheek-pieces may be still more separated so as not to bring the levers into operation at all, the sliding bars being of such length as to permit the levers to pass within the space between them, and provided with projections upon their ends, against which the cheek-pieces bear when fully distended.

The form of levers shown in Fig. 4 may be substituted for that shown in the other figures.

What I claim as my invention, and desire to secure by Letters Patent, is—

A bit for use in the mouths of horses and other animals, combining in its construction, sliding bars A A¹, cheek-pieces A² A², and levers B B and link B', the parts being arranged substantially as and for the purpose set forth.

In testimony whereof I have signed my name to this specification in the presence of two subscribing witnesses.

NAHUM HAYWARD.
